UNITED STATES PATENT OFFICE

CHRISTIAN MESSNER, OF TROSSINGEN, GERMANY

POCKET CASE

Application filed November 30, 1927, Serial No. 236,688, and in Germany August 18, 1925.

My invention relates to pocket cases, having two hinged halves, for instance cigarette cases, match boxes and the like. It is an object of my invention to provide a pocket case 5 of the kind described which upon being opened will present its contents in a convenient position for handling.

To this end I provide means operatively connected with the halves of the pocket case 10 by which upon opening the case, the objects therein contained are automatically moved forward and away from the body or shell in which they are stored, and, upon closing the case, are automatically returned to their initial position in the body or shell.

It has already been suggested to provide holders for the objects enclosed in pocket cases which are pivotally carried in the body or shell of a pocket case so as to be raised 20 therefrom, however these objects were not moved forward, and it will be understood that it is more convenient for the user to have the object presented in such manner as to project beyond the edge of the pocket case.

25 In the drawings affixed to this specification and forming part thereof two forms of pocket cases embodying my invention are illustrated diagrammatically by way of example.

In the drawings 30 Figs. 1, 2, 3, and 4 illustrate a case in which the holders for the objects are controlled by a flexible part such as a cord or the like.

Figs. 5, 6, and 7 illustrate a case in which the holder is under positive control.

35 More particularly Fig. 1 is a plan view of the case in open condition, with one of its holders partly broken away.

Fig. 2 is a part end elevation showing the 40 cord or the like by which the holder is controlled.

Figs. 3 and 4 are sections on the line 3 III—III in Fig. 1, showing the holder in its initial and in its advanced position, respectively.

45 Fig. 5 is a plan view of the second type of case, with the holder partly broken away, and the lid opened.

Fig. 6 is an end elevation of the case.

50 Fig. 7 is a section on the line VII—VII

in Fig. 5, with the holder in the position illustrated in dot-and-dash lines in Fig. 5.

Referring first to Figs. 1 to 4, 1 and 2 are the two halves of a cigarette case which are connected by a hinge 3 and are each provided with a holder 5 which is adapted to slide longitudinally in its half, that is, in parallel to the axis of the hinge 3.

The holders 5, 5 are trays of substantially U-shaped cross section and provided with the usual buckles 25 and resilient straps 26 for holding the cigarettes 4, and a shoulder formed by a cover plate 27 for the mechanism and serving as a support for the cigarettes. 60 8, 12, and 9, 13 are pins projecting from the flanges of the holders at various levels and pitched some distance apart. The pins 8, 9 engage in ways constituted by parallel flanges 10, 10 extending along the longitudinal edges of the halves and plates 11, Figs. 3 and 4, each of which is provided with a shoulder 24 at its upper end. The pins 12, 13 in their initial position are flush with the back of the corresponding half and cooperate with cams 14, 14 each having a short gradient and a 65 longer parallel face as shown in Figs. 3 and 4.

70 Mechanism is provided for advancing the holders in parallel to the axis of the hinge 3 and it will be understood that in being thus advanced, the ends of the holders from which the cigarettes project, are raised beyond the upper edges 15, 16 of the corresponding halves by the cams 14. Such mechanism comprises a cord, wire or the like 17, extending across the hinge of the halves, threaded through holes in flanges at the lower edge of each half, and engaging at either end an angular lever 20 which is fulcrumed on a pin 18 in the corresponding half 1, 2 and provided with a pull-back spring 19 engaging the shorter 75 arm of each lever. 21 is a pin at the end of the longer arm and 22 is a slot in a plate 23 which projects from the shoulder of the cover plate 27 intermediate the cover plate and the back of the corresponding half.

80 The length of the cord 17 is such that with the case closed the levers 20 are in the position illustrated in Fig. 1, their long arms extending in parallel to the lower edges of the halves, in which position they are held by 85

90 Fig. 6 is an end elevation of the case.

95 Fig. 7 is a section on the line VII—VII

pull-back springs 19. When the case is opened, the distance of the points where the cord 17 is attached to the levers 20 is increased so that the cord 17 rocks the levers into the position shown in dotted lines in Fig. 1 in which they advance their holders toward the upper edges 15, 16 of the respective half. As appears from Figs. 3 and 4 the pins 8, 9 move in parallel while the holders 10 are being advanced and the pins 12, 13 rise on the cams 14, 14 so that the holders are raised beyond the edges 15, 16 and, upon the halves being moved further apart, the pins 12, 13 slide on the parallel portions of the cams 14, 15 and the pins 8, 9 slide in their ways, pushing the cigarettes 4 across the edges 15 and 16, as shown in Fig. 4, as far as permitted by the shoulders 24 of the plates 11.

It will be understood that this movement 20 of the holders while conserving the advantage of pivotally carried holders—as the holders in being raised by the cams 14, rock about the pins 8, 9—provides the further advantage of advancing the objects beyond the 25 case so that they are readily handled without interference on the part of the case.

Referring now to Figs. 5 to 7, these show positive means for operating the holders 5. In the example illustrated, only one holder 5 30 is provided in the half 1, but obviously I am not limited to a single holder. Identical parts have been marked with the same reference numerals as in Figs. 1 to 4. In this example, in order to reduce the height of the pocket 35 case, the cover plate 27 has been dispensed with and the mechanism has been arranged below the holder 5, a shoulder 33 being formed at the lower end of the holder by bending it into channel section as shown in Fig. 7. 28 is 40 a pin on the half 2, 29 is a projection on a lever 30 fulcrumed at 31 in the other half 1, 32 is a tooth projecting from the opposite end of the lever 30 and adapted to engage the channelled shoulder 33 of the holder 5, and 45 34 is a spring which tends to hold the lever 30 in the position illustrated in Fig. 5, that is, adjacent the lower edge of the case.

It will be understood that when the case has 50 been opened to a given extent, the pin 28 engages the projection 29 on the lever 30 as shown in Fig. 6 and while the lid 2 is moving into the position illustrated in dot-and-dash lines in Fig. 6 the lever 30 advances the 55 holder 5 toward the upper edge 15 of the half 1. An inclined face 35 is provided adjacent the edge 15 so as to raise the end of the holder beyond the edge as shown in Fig. 7, while it is being advanced by the lever 30.

60 Pins 42 and 44 are provided at opposite sides of the holder 5 and engaging, respectively, below a flange 43 at the outer edge of the half 1 and in an inclined slot 45 in a vertical flange 46 depending from the flange at 65 the inner edge of the half 1. These pins

guide the holder on its upward movement and limit its movement with respect to the half 1.

It is not desirable that the rear face of the holder and the back of the half 1 should be in sliding contact throughout, as this would cause excessive friction and therefore crozes or depressions are formed in the holder at 47 and 48 which constitute projections on the rear of the holder on which the holder slides. The lower edge of the channel section 33 may also be adapted to slide on the back of the half 1.

70 I do not wish to be limited to a case having a definite number of holders nor to any material of which the case, or any of its parts, is made, and in general I wish it to be understood that I do not desire to be limited to the exact details of construction shown and described for obvious modifications will occur to a person skilled in the art.

75 I claim:

1. A pocket case comprising hinged halves, a movable holder in one of said halves, means for guiding said holder in a combined advancing and rocking movement, a lever pivotally carried in said half and adapted to engage said holder, and means controlled by the relative displacement of said halves so as to impart rotation to said lever and to move said holder when said halves are turned on their hinge so as to open said case.

90 2. A pocket case comprising hinged halves, a movable holder in one of said halves, means for guiding said holder in a combined advancing and rocking movement, a lever pivotally carried in said half and adapted to engage said holder, and a projection on the other half adapted to engage said lever so as to impart rotation to said lever and to advance said holder when said halves are turned on their hinge so as to open said case.

95 3. A pocket case comprising hinged halves, a holder arranged in one of said halves, means controlled by the relative displacement of said halves for advancing said holder, and an inclined face on said half adapted to be engaged by the edge of said holder so as to rock said holder beyond the edge of said half.

100 4. A pocket case comprising hinged halves, a movable holder in one of said halves, means for guiding said holder in a combined advancing and rocking movement, a shoulder at one end of said holder, a lever pivotally carried in said half and adapted to engage said shoulder, and means on the other half 105 adapted to impart rotation to said lever and to move said holder when said halves are turned on their hinge so as to open said case.

110 In testimony whereof I affix my signature.

CHRISTIAN MESSNER.
